(57) **CLAIM**

The ornamental design for a packing box, as shown and described.

DESCRIPTION

FIG. 1. is a front perspective view of a packing box showing our design.

FIG. 2. is a bottom rear perspective view of the packing box.

FIG. 3. is a front elevation view of the packing box of FIG. 1.

FIG. 4. is a rear elevation view of the packing box of FIG. 1.

FIG. 5. is a left side elevation view of the packing box of FIG. 1.

FIG. 6. is a right side elevation view of the packing box of FIG. 1.

FIG. 7. is a top plan view of the packing box of FIG. 1.

FIG. 8. is a bottom plan view of the packing box of FIG. 1; and,

FIG. 9. is a sectional view taken along line 9-9 of FIG. 7. The dash-dash broken lines in the drawing depict portions of the packing box and form no part of the claimed design. The dash-dot broken lines shown in the FIG. 7 indicate a sectional line and form no part of the claimed design.

1 Claim, 9 Drawing Sheets
